TOOL COMPANY, OF HOUSTON, TEXAS, A CORPORATION OF TEXAS

CORE CATCHING DEVICE

Application filed August 18, 1930. Serial No. 476,300.

Our invention relates to devices for engaging and breaking off the core in well drilling when obtaining a sample of the formation being drilled.

5 We have as an object to mount the core-engaging dogs firmly and securely without the use of springs or similar means tending to clog up.

We also aim to provide a securing means 10 for the core engaging dogs which will not become loosened and fail to function.

It is also an object to provide a relief for 15 vacuum tending to form between the telescoping parts in the operation of the core engaging devices.

The invention resides in the general construction and assembly of parts making up the complete core catching apparatus.

The invention is an improvement upon the 20 construction shown in the prior application of Floyd L. Scott filed June 29, 1929, Serial No. 374,849, now matured into Patent No. 1,808,009, dated June 2, 1931.

The core drill employed with our core 25 catcher may be of any desired construction. We have shown a soft formation drill including a head 1 of tubular formation, tapered downwardly on its outer periphery. It has an upper shoulder 2 and an interiorly threaded 30 socket 3 to engage the shank 4 of the special drill collar 5. The shoulder 1 has an annular channel 6 arranged to receive the flushing fluid from passages 7 in the drill collar and direct it into passages 8 through the bit head 35 to the forward side of the cutting blades 9.

There are three or more cutting blades extending laterally from the head, and extending slightly in advance thereof.

Above the head and between the shoulder 40 2 and the lower end of the drill collar is a wear plate 10. Said plate is a washer serving to take up the wear from the flushing fluid. It has openings therein registering with the passages 7 in the head. When the 45 erosion of flushing fluid on this washer is great enough to cause leakage it may be replaced.

The drill collar has an upwardly extending sleeve 11. A core barrel 12 is screwed to the 50 inner lower end of the sleeve and the interior

of the sleeve is spaced from the barrel above their point of engagement. Adjacent the lower end of the drill collar, a plurality of openings 13 are formed to allow the projection therethrough of the core engaging dogs 14. The upper walls of these openings are squared off, but the lower walls are beveled downwardly and outwardly.

The sleeve 11 of the drill collar fits within an outer drill sleeve 15 which connects with the drill stem 16 at its upper end and telescopes over the sleeve 11 at its lower end. As seen in Fig. 2, the drive sleeve, has downwardly extending arms 17 fitting within grooves in the outer surface of the drill collar 65 and serving as a support for the core engaging dogs 14 at their lower ends.

The drill collar and drive sleeve are secured together by radial pins 19 upon the drill collar fitting within slots 20 in the drive 70 sleeve. The pins are screwed within openings in the drill collar and have diametrical grooves 21 in the outer ends to receive locking pins 22 which lie within grooves in the outer face of the drive sleeve to prevent unscrewing of the pins 19. The walls of the grooves in which the pins 22 are fitted are peened over to prevent removal of this locking means. The drive sleeve is allowed a longitudinal movement over the sleeve 11 80 limited by the length of the slots 20.

The upper end of the drill collar is recessed slightly on its inner face at 23 to receive a packing sleeve 24 of hard but expandable material which is received in a recess in 85 the drive sleeve at its upper end. This packing sleeve serves to prevent loss of flushing fluid between the sleeves 11 and 15 in use. A plurality of vents 25 are provided through the drive sleeve to allow equalizing of pressure on the packing sleeve in operation.

The dogs 14 are mounted in blocks 26 fitted within recesses on the meeting faces of the drive sleeve and drill collar. The dogs are pivoted to the blocks at 28. Their upper ends 95 are beveled to slide through the openings 13 in the drill collar and to fill said openings when in normal position. The blocks are held against removal on the ends of arms 17 by screws 27, the heads 29 of which are adapted 100

to be upset into a lateral recess 30 in the outer end of the arm 17 as seen in Fig. 2.

When the drill is in operation, the parts will appear as shown in Fig. 1. The dogs 5 will be retracted and the packing sleeve 24 will fit closely in its seat. When a core of sufficient length has been obtained, the operator will stop rotation and pull upwardly upon the drill stem and drive collar. The 10 pressure of the pumps and the weight of the drill will hold the drill on the bottom of the hole, and the relative upward movement of the drive sleeve will move the dogs upwardly and inwardly into the position shown in Fig. 15. 3. The pins 19 will limit the relative movement of the drill collar and drive sleeve, and the bit will be withdrawn together with the core broken off by the dogs.

When the drive collar moves upwardly 20 relative to the drill collar there will be a suction in the space outside the packing sleeve 24 which, without the relief provided by the opening 25, would tend to unduly expand and rupture the packing sleeve. But fluid may 25 enter from the outside preventing the vacuum tending to form and allowing free movement of the sleeves relative to each other.

By securing the blocks 26 and the dogs firmly in position by the screws 27 as described, the action of the dogs is a positive one not liable to fail in use. When the dogs are to be removed, the heads of the screws 27 will be cut away by a chisel sufficiently to allow its unscrewing.

35. What we claim as new is:

1. A core drill including a drill collar, a drill bit thereon, said drill collar having an upwardly extending sleeve thereon, a drive sleeve telescoping over said drill collar, an 40 interior packing sleeve at the upper end of said drill collar, a vent connected with the outer side of said packing sleeve, and core-engaging means actuated by the relative movement of said collar and drive sleeve.

45. 2. A core drill including a drill collar, a drill bit thereon, said drill collar having an upwardly extending sleeve thereon, a drive sleeve telescoping over said drill collar, an interior packing sleeve at the upper end of 50 said drill collar, means to approximately equalize the pressure on both sides of said packing sleeve, and core engaging dogs on said drive sleeve actuated by the upward movement of said drive sleeve relative to said drill collar.

55. 3. A core drill including a drill collar, a drill bit thereon, a drive sleeve telescopically engaging said drill collar, means to prevent relative rotation and to limit longitudinal movement between said collar and said sleeve, core engaging dogs, blocks on which said dogs are mounted, screws securing said blocks to said sleeve, and means to prevent unscrewing of said screws.

60. 4. A core drill including a drill bit, a drill

collar thereon, a drive sleeve fitting over said collar, a packing sleeve between the upper end of said collar and said drive sleeve, said packing sleeve being slid able relative to said drive sleeve, means to allow a limited longitudinal play of said drive sleeve on said drill collar, core engaging means actuated by said longitudinal play, and means to relieve the partial vacuum tending to form outside said packing sleeve when said drive sleeve is drawn upwardly.

In testimony whereof, we hereunto affix our signatures, this the 11th day of August, A. D. 1930.

FLOYD L. SCOTT.
HENRY T. BAGGETT.
